UNITED STATES PATENT OFFICE.

JOHN H. LAWRENCE, OF STERLING, ILLINOIS.

DOOR-HANGER.

SPECIFICATION forming part of Letters Patent No. 363,148, dated May 17, 1887.

Application filed March 30, 1886. Serial No. 197,912. (No model.)

To all whom it may concern:

Be it known that I, JOHN H. LAWRENCE, a citizen of the United States, residing at Sterling, in the county of Whiteside and State of Illinois, have invented certain new and useful Improvements in Door-Hangers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention has reference to that class of barn-door hangers in which the door is supported and carried on two horizontal bars, which are attached to the upper portion and rest, respectively, on the ends of the axle of a carrying-wheel, the latter having its tread on a suitable track attached to the barn; and my invention pertains, especially, to a novel construction of that part of the hanger which includes the horizontal bars aforesaid and is attached to the door.

The advantages of my construction are its simplicity and the fact that in the peculiar form shown in my invention all of the parts may be formed of straight steel bars, and thus rendered strong, light, and durable.

As the carrying-roller and the portion attached to the building are of the usual and well-known form, and nothing is herein claimed in reference thereto, I do not deem it necessary to particularly show or describe such parts.

In the drawings, Figure 1 is a perspective of that portion of the hanger embodying my invention. Fig. 2 is a view of the top of the same. Fig. 3 is a detail of the two parts employed in the construction of my invention.

A is a steel bar, originally straight, but bent laterally by means of dies to form three sides of substantially a square, consisting of the horizontal part *b* and vertical portions *g g*. The part *b* rests upon one end of the axle of the carrying-roller, the angles *a a*, formed by the junction or relation of the part *b* with the parts *g g*, serving, respectively, as stops for such roller.

B is a steel bar, also originally straight, having its ends bent laterally by means of dies, so as to form loops *C* at each end, such loops

extending far enough beyond the part *b* of the bar A when A and B are put together, as shown, to permit the axle of the carrying-roller D to traverse the entire under surface of the part *b* without the tread of such roller coming in contact with the loop C. The bar B has also, by means of dies, its central portion thrown slightly upward for a distance corresponding to the length of the part *b* of bar A, whereby stops or angles *d d* are formed on the lower side of the bar B, corresponding in relative distance to the angles or stops *a a* of the bar A. When the bars A and B are thus shaped, they are fastened together by bringing the open ends of the loops C respectively against the side of the bar A at the angles in the latter and passing a rivet, *e*, transversely through both bars. The ends or sides *g g* are suitably bolted to the door.

The roller D (having its tread in the usual way astride a ledge on the building) is placed between the horizontal portion of the bar A and the bar B, the part *b* of the bar A resting on one end of the axle of such roller, and the lower edge of the raised portion of the bar B resting on and forming a track for the other end of such axle.

It will be seen that the device is very simple and easily constructed, and, being made from steel bars, is extremely strong and durable.

The utility of my invention over similar prior devices consists in the fact that it is constructed of but two parts, whereby ease and cheapness of construction are attained, the number of points of interattachment reduced, and, as a consequence, the liability of separation of parts lessened. Again, there being no vertical loops, rollers of any diameter can be used, and with the ordinary roller less room is required above the door; but the main advantage is that, the loop C being formed on the horizontal part B and the extreme ends of the loops being attached to the plate A, such loops are rigidly held at each end thereof, while in former constructions the open ends of the loops had no support other than a mutual connection laterally, which in no degree prevented them from opening in the line of their bow. In my invention there are no unsupported ends.

What I claim as my invention, and desire to

secure by Letters Patent of the United States,
is—

1. In a door-hanger, the combination of the
bar A, bent to form a horizontal central part,
5 b, and ends g g at an angle with part b, and
the bar B, having recesses d d in its lower
edge and its ends bent laterally to form loops
C, the ends of such loops being respectively
rigidly fastened to the bar A at or near the
10 angles of the latter, substantially as shown,
and for the purpose described.

2. In a door-hanger, the combination of the
bar A, having the central horizontal portion,
b, and vertical supporting ends g g, the bar B,
15 provided with laterally-bent ends C, and placed
parallel with the portion b of bar A and its ends
attached to bar A at the angles a of the lat-
ter, and the roller D, supported on a track,
and its axis adapted to roll under and sup-

port the portion b and an equal length of the 20
bar B, substantially as shown, and for the pur-
pose described.

3. A door-hanger consisting of hanger-ways
formed of a bar or bars arranged with the
longer axis in vertical plane, with lateral bends 25
at the ends of the ways, in combination with
the vertical supports attached thereto, and a
wheel having an axis running upon the ways,
said wheel being adapted to run upon the track,
substantially as shown, and for the purpose 30
described.

In testimony whereof I affix my signature in
presence of two witnesses.

JOHN H. LAWRENCE.
